Patented Oct. 3, 1961

191,481

PEN CARTRIDGE FILLING TOOL

Howard W. Conley, West Shore Drive,
Detroit Lakes, Minn.

Filed Oct. 18, 1960, Ser. No. 62,528

Term of patent 3½ years

(Cl. D74—1)

Fig. 1

Fig. 2

Fig. 3

FIG. 1 is a top plan view of a pen cartridge filling tool showing my new design;

FIG. 2 is a side elevational view, a similar appearance being presented from all sides; and

FIG. 3 is a bottom plan view thereof.

I claim:

The ornamental design for a pen cartridge filling tool, as shown and described.
